ATTORNEY

UNITED STATES PATENT OFFICE

GREGORY LANG, OF YUBA CITY, CALIFORNIA

FRUIT PICKER'S STILT

Application filed May 12, 1930. Serial No. 451,555.

This invention relates to stilts, and particularly to a type designed especially for the use of fruit pickers, pruners, and other orchard workers, to take the place of the ladders such as are now commonly employed in connection with the above operations. The ladders of course must be frequently moved from one point to another, even when working on any one tree, and the accompanying cessation of picking or other operations during such movements, consumes considerable time in the aggregate and cuts down the output of the individual workers to an appreciable extent.

The principal object of my invention is to provide stilts for the workers so constructed that they are practically self-balancing, and so that the movements of the individual are facilitated and he can thus devote his entire attention to fruit picking or other operations rather than to balancing himself, as is necessary with the ordinary stilts. The stilts are also constructed so that walking is comparatively easy, the movements are not accompanied by jars or shock to the person as is usually the case, and the stilts do not tend to sink down in the loose ground around the trees as would the ordinary stilts.

A further object of the invention is to provide a means for securing the feet and legs of the workers to the stilts in such a manner that the stilts are retained in proper vertical and longitudinal alinement regardless of any irregularities in the shape or alinement of the legs or feet of the wearer, thus enabling him to stand normally without any tiring strain being imparted to his limbs.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a perspective view of a stilt as strapped to a leg.

Fig. 2 is an enlarged fragmentary cross section of the upper portion of a stilt.

Referring now more particularly to the characters of reference on the drawing, the numeral 1 denotes a platform for a foot of the wearer, from the ends of which a pair of diverging legs 2 depend the desired distance and of course governing the height of the stilt.

A ground supporting bar 3 extends between and is secured to the lower ends of the legs, this bar being preferably in the form of a rocker whose center of curvature is adjacent the platform. The rocker is preferably resilient so that it may yield vertically, and is faced on the bottom with a replaceable strip 4 of leather, rubber, or other material so as to take the wear from the rocker itself. The latter may therefore be made of relatively cheap material without danger of its wearing out quickly.

The platform adjacent its rear end is provided with a fixed heel-engaging seat or cradle 5, said cradle having a strap 6 to pass over the front of the boot of the wearer adjacent its junction with the leg portion, as shown in Fig. 1. Mounted on the platform toward the front of the same are opposed laterally adjustable lugs or stops 7. These are adapted to engage the sole of the boot on opposite sides and toward the toe and have straps 8 associated therewith to pass over the boot adjacent the toe. By means of the above construction the boot is secured to the platform against vertical play, and the platforms of the two stilts and consequently the stilts as a whole are retained substantially parallel to each other regardless of any in or out turning of the feet of the wearer. Secured to and extending between the legs of the same a distance below the platform is a cross-bar 9 to which are individually and pivotally secured, for individual longitudinal adjustment, the lower ends of the leg braces 10. These braces extend upwardly past the sides of the platform and thence alongside the leg of the wearer to terminations adjacent the plane

of the knee. Adjacent their upper ends said braces slidably support a leg engaging band 11 of leather or the like, which is adapted to be strapped about the leg just below the knee. Where the braces extend 5 past the platforms they are engaged by straps 12 which are removably and adjustably secured to the sides of the platform for movement lengthwise of the same. These straps 10 are preferably somewhat longer than the width of said leg braces, so as to allow for a certain amount of play of the legs, backward and forward, relative to the stilts. This enables the wearer to have a certain amount 15 of leg movement, without moving the stilts, as when operating on trees with the stilts more or less firmly set in the soft ground. If such play of the leg braces is not desired, the space between the straps and braces may 20 be filled with blocks of rubber or the like. By means of this arrangement not only may the braces be shifted along the platform while retaining them in a vertical position; but by adjusting either the bottom or the 25 intermediate connections of the braces with the stilt parts, they may be angled one way or the other relative to a vertical plane, as the convenience of the wearer and the particular alinement of his legs may require. 30 Also by initially removing the braces, shims as at 13 may be placed between the braces and the platform and bar 9 in opposed alternating relation, as shown in Fig. 2. The braces may thus be disposed at a transverse 35 angle to a vertical plane and to the legs 2, if the legs of the wearer are bowed or otherwise out of plumb so that the braces will extend parallel to his legs without straining the latter or without causing the stilts to be 40 out of plumb.

The provision of the rocker form of support for the stilts not only gives the same a relatively large ground bearing area so that they will not sink so readily into soft 45 ground, but enables the wearer to easily retain his balance by suitable foot pressure and to walk or advance himself with a smooth rolling action of the stilts rather than a stiff jerky one, and without the necessity of the feet being raised to any great extent. Also on account of the use of the leg 50 braces the movements of the stilts, when operating over rough ground, are controlled from the legs of the wearer instead of his 55 feet, and no strains are placed on the latter. The resilient nature of the rockers provides a cushioning support for the wearer, without interfering with the rolling or rocking movement of the stilts when walking.

60 From the foregoing description it will be readily seen that I have produced such a device as substantially fulfills the objects of the invention as set forth herein.

65 While this specification sets forth in detail the present and preferred construction

of the device, still in practice such deviations from such detail may be resorted to as do not form a departure from the spirit of the invention, as defined by the appended claims.

Having thus described my invention what I claim as new and useful and desire to secure by Letters Patent is:

1. A stilt comprising a vertical frame topped by a foot plate, the frame including a cross bar below the foot plate and substantially parallel therewith, a pair of separate leg braces one pivoted on each side of the cross bar and extending upwardly along the side of and above the foot plate, a leg strap connecting the leg braces above the foot plate, a bracket on each side of the foot plate extending around one of the leg braces, the brackets being relatively longer than the width of the braces to allow the leg braces to rock on their pivot points on the cross bar with a slight fore and aft movement relative to the frame and foot plates. 75 80 85 90

2. A stilt comprising a vertical frame topped by a foot plate, the frame including a cross bar below the foot plate and substantially parallel therewith, a pair of separate leg braces one pivoted on each side of the cross bar and extending upwardly along the side of and above the foot plate, a leg bracket on each side of the foot plate extending around one of the leg braces, the brackets being relatively longer than the width of the braces to allow the leg braces to rock on their pivot points on the cross bar with a slight fore and aft movement relative to the frame and foot plates, and removable blocks for insertion between a bracket and foot plate on one side of the stilt and between the lower end of the opposite brace and its adjacent cross bar, whereby the braces may be laterally adjusted at an angle to the vertical axis of the frame. 95 100 105 110

In testimony whereof I affix my signature. 110
GREGORY LANG.
